UNITED STATES PATENT OFFICE.

CARL ANDERSON, OF WESTBROOK, MINNESOTA.

FENCE-WIRE REEL.

1,108,311.

Specification of Letters Patent. Patented Aug. 25, 1914.

Application filed December 13, 1913. Serial No. 803,715.

To all whom it may concern:

Be it known that I, CARL ANDERSON, a citizen of the United States, residing at Westbrook, in the county of Cottonwood 5 and State of Minnesota, have invented a new and useful Fence-Wire Reel, of which the following is a specification.

My invention relates to reeling devices for barbed wire and other kinds of wire used especially for fences; and the object 10 is to provide a portable wire reeling device, which may be carried in a wagon or other vehicle and which may readily be folded so as to allow a roll of wire to be placed on it 15 or removed from it; and for said purpose the shaft of the reel is also detachable from the frame.

In the accompanying drawing, Figure 1 is a top view of my improved wire reeling 20 device with the three uppermost arms of the reel broken away. Fig. 2 is a side-elevation of the device shown in Fig. 1 with the crank omitted. Fig. 3 is an end elevation of the frame of the device with all mechanism 25 omitted.

Referring to the drawing by reference numerals, 1 designates the frame of the device, which may be of any suitable skeleton form and provided with legs 2. It is provided with two journal boxes 3, in which a shaft 4 is mounted and provided with a hand crank 5 and two collars 6 which prevent sliding movement of the shaft. On said shaft is fixed within the frame the hub 7 of the wire reel, which consists of said hub and a series of radial arms 8, each of which has its outer end provided with a curved finger 9, which finger together with a similar finger 9^a form a crutch 10 into which the wire is reeled.

In order to facilitate the placing and removing of a roll of wire from the reel, each finger 9^a is formed on a secondary radial arm 8^a, which is pivoted at 11 to the primary arm 8, or any other suitable part of the reel, and is connected by a link 12 with a sleeve 13, which is slidable on the shaft 4 and carries a finger lever 14, which lever is fulcrumed at 15 and is pressed by a spring

16 so as to normally engage by its tooth 17 50 in a cavity 18 in the side of the shaft, said tooth extending through a radial aperture in the sleeve 13.

In the operation of the device, the frame 1 is placed in a wagon or other vehicle. If 55 the wire is to be unreeled as in the building of a fence, the roll of wire is placed on the reel, the end of the wire secured to one of the fence posts and the vehicle drawn along the line of the fence posts until the 60 wire is unreeled and placed in position for securing it to the posts. And if fence-wire is to be taken down, it is loosened from the posts, one end of it secured on the reel and the reel turned by a person in the wagon, 65 while the wagon is being drawn along about as fast as the wire is rolled onto the reel; or if the wire is not barbed, nor very long, the wagon may stand still and the wire slid along on the ground. When a roll of wire 70 is to be placed on the reel or removed therefrom, the operator presses on the finger lever 14, so as to disengage it from the cavity in the shaft, and by moving the sleeve away from the reel hub the links and the 75 fingers 9^a are folded to the position shown in dotted lines in Fig. 1, while the roll of wire is passed over said fingers; and in order to pass the roll of wire over the end of the shaft 4, the latter is lifted out of its 80 journal boxes. For purpose of thus removing and replacing the shaft the caps 3^a of the journal boxes are hinged at 3^b and have their unhinged ends held down by thumb-catches 3^c, turning on pivots 3^d. 85

What I claim is:—

In a device of the class described, the combination with a shaft and means for rotating the same, of a reel having radial arms with crutch-shaped outer ends forming the wire-holding parts of the reel; each of said radial arms composed of a rigid primary arm with half of the crutch on it and a secondary arm pivoted near the hub of the reel and having the other half of the 95 crutch fixed on it, a sleeve slidable on the shaft and having a spring-pressed catch adapted to engage a cavity in the shaft when

the primary and the secondary arms are in parallel position, links connecting each secondary arm with the sleeve so as to raise said arms and brace them in normal position, said shaft having a cavity in which the catch engages when the secondary arms are in normal position.

In testimony whereof I affix my signature, in presence of two witnesses.

CARL ANDERSON.
